ELECTROMAGNETIC SEWING MACHINE

Frederick Diehl, Elizabeth, N. J., assignor to The Singer Manufacturing Company, Elizabeth, N. J., a corporation of New Jersey

Application January 9, 1940, Serial No. 313,023

8 Claims. (Cl. 112—221)

This invention relates to sewing machines and has for an object to provide a sewing machine with improved electromagnetic means for operating one or more of the component mechanisms 5 of the machine, so that all mechanical connections between such mechanism and the other component mechanism or mechanisms of the machine may be eliminated.

The aims in view are attained by operating 10 a selected one of the component mechanisms of the machine by means of a specially constructed solenoid having a movable core of lightweight which may be given controlled series of impulses or steps between its extreme positions. Preferably, the present solenoid is applied to the end- 15 wise reciprocating needle-bar of the sewing machine to eliminate all mechanical connections from the overhanging bracket-arm of the machine. By means of the present solenoid, the 20 needle-bar is caused to descend in a plurality of steps, pause in its lower position for seizure of the needle-thread loop by the loop-taker, and subsequently rise in a plurality of steps to the limit of its upstroke.

25 In the accompanying drawings Fig. 1 is a side elevation, partly in section, of a sewing machine embodying the invention. Fig. 1^a is a sectional view of the needle-bar-operating solenoid of Fig. 1, with the core piece or armature in a 30 position intermediate its extreme positions. Fig. 2 is a bottom plan view of the machine. Fig. 3 is an end elevation of the bracket-arm head, which carries the needle-bar and its operating solenoid. Fig. 4 is a plan view of the end-portion 35 of the machine-bed underlying the needle-bar. Fig. 5 is a section on the line 5—5, Fig. 2. Fig. 6 is a section on the line 6—6, Fig. 2. Fig. 7 is a section on the line 7—7, Fig. 2. Fig. 8 is a vertical section taken longitudinally of the 40 machine-bed through the axis of the loop-taker which is about on the line 8—8, Fig. 4. Fig. 9 is a diagrammatic illustration of the movements of the needle-bar and loop-taker over one complete stitch-forming cycle. Fig. 10 is a diagrammatic illustration of the circuit containing the 45 several sections or energizing coils of the solenoid and their controlling switches and Fig. 11 is a development of the cam-cylinder which operates the solenoid-controlling switches.

50 The machine is constructed with a frame including the flat rectangular bed 1 from one end of which rises the standard 2 of the overhanging bracket-arm 3 terminating in the head 4 which carries the three-coil solenoid 5 for operating the 55 needle-bar 5 and needle 6.

The solenoid 5 comprises the inner brass tube 7 on which are tightly press-fitted the steel disks 8, 9, 10, 11, which are equally spaced apart by the intervening Bakelite insulating sleeves 12 to provide winding spaces for the magnet wire coils 13, 14, 15 all of which are preferably wound in the same direction so as to have the same polarity. After the magnet wire coils are wound between the equally spaced disks 8, 9, 10, 11, a cylindrical 10 steel shell 16 is tightly fitted to the peripheral edges of the disks. End-caps 17, 18 of non-magnetic material, such as aluminum, are fitted to the ends of the shell 16 and held by screws 19 which enter the top and bottom disks 8 and 11. This complete unitary solenoid assembly 5 is 15 fitted to a seat 20 in the head 4 and fastened to said seat by screws 21 so as to be rigid with said head 4 and bracket-arm 3. The top end-cap 17 is fitted with a top bearing bushing 22 for the needle-bar 5 the bottom bearing 23 for which 20 is in the lower end of the head 4. The bottom end-cap 18 of the solenoid 5 is formed with a needle-bar clearance opening 24.

The needle-bar 5 has fixed thereto, within the solenoid core tube 7, a comparatively short steel core-cylinder or armature 25 of lightweight. The armature 25 is of a length to reach approximately from the plane of the bottom face of the solenoid disk 8 to the plane of the top face of the solenoid disk 10, as shown in Fig. 1^a. 25 When one of the magnet coils is energized by a direct current of electricity, the steel disks immediately adjacent the energized coil become magnetized and present annular magnetic poles of opposite polarity at their central apertures. 30 These poles will draw the armature 25 to a position bridging the gap between such poles, as shown in Fig. 1. When two adjacent magnet coils are simultaneously energized the steel disk immediately above the upper coil and the steel 35 disk immediately below the lower of the two energized coils will present annular magnetic poles of opposite polarity. The intermediate steel disk will have no polarity and the armature 25 will shift its position one step, as from that shown 40 in Fig. 1 to that shown in Fig. 1^a, so that it will bridge the gap between the disks 8 and 10. On the downstroke of the needle-bar the magnet-wire coils are preferably energized in the following sequence: beginning with coil 13 energized, 45 the next step is to energize coil 14 while maintaining coil 13 energized. This causes the needle-bar to descend one step or from the position shown in Fig. 1 to the position shown in Fig. 1^a. 50 Following this step the coil 13 is de-energized 55

whereupon the needle-bar descends another step so that the armature will bridge the gap between disks 9 and 10. For the third step in the descent of the needle-bar, coil 15 is energized 5 while maintaining the energization of coil 14. Finally, coil 14 is de-energized and the needle-bar makes the last step of its downstroke. Thus, the armature 25 and needle-bar 5 may be made to travel by short stages or steps from one extreme position to the other, by energization and de-energization of selected magnet coils at the proper times, as will be evident to those skilled in the art. Cushioning washers 26 of felt, cork or the like are preferably provided within the end-caps 17, 18 to yieldingly and quietly limit the endwise movements of the armature 25 and needle-bar 5.

The needle-bar 5 has fixed thereto a block 27 which pivotally carries the needle-thread take-up lever 28 having a thread take-up eye 29. The lever 28 has a bifurcated tail 30 which engages the stationary pin 31. The take-up lever 28 has a curved extension 32 beyond the thread-eye 29 which serves as a guard to prevent the slack 25 needle-thread from looping over the top-edge of the lever 28 when the latter drops to give slack to the needle-thread for the loop-casting excursion of the oscillatory hook or loop-taker to be described.

Slidably mounted in the head 4, behind the needle-bar 5, is the hollow presser-bar 32 carrying the presser-foot 33. The presser-bar 32 houses a presser-spring 34 engaged at its upper end by the lower end of the adjustable screw-pin 35 the head 36 of which is threaded into the frame-lug 37. The presser-bar has fixed to its upper end the block 38 which is engaged by the usual presser-lifter cam-lever 39. The head 4 also carries the needle-thread tension-device 40. The needle-thread *t* runs from the supply to the stationary guide-hook 41 on the outside of the solenoid casing; thence to and through the tension-device 40; thence under the usual presser-bar controlled guide-bar 42; thence upwardly to and around the stationary thread-guide 43; then down to and around the stationary thread-guide 44; thence through the take-up eye 29; thence downwardly through the thread-guide tube 45, which is carried by the 50 needle-bar, to the eye of the needle.

Journaled in bearing lugs below the bed 1 is the rotary main-shaft 46 carrying the belt-pulley 47 which is wrapped by the belt 48 running around the pulley 49 of the conventional 55 sewing machine driving motor 50 fixed externally of and to the bracket-arm standard 2.

Cooperating with the needle 6 in the formation of stitches is the oscillatory loop-taker 51 having the loop-taking hook 52 which seizes 60 thread-loops from the needle and casts them about the lower stationary bobbin-thread case 53. The loop-taker 51 is carried by a shaft 54 to which is fixed a crank-arm 55 connected by a link 56 to one arm 57 of a lever the other arm 65 58 of which is connected by the link 59 to another lever 60 which is vibrated by the grooved cam-cylinder 61. The present loop-taker 51, bobbin-case 53 and driving parts 55, 56, 57 and 58 are constructed substantially in accordance 70 with the disclosure of U. S. Patent No. 663,696; Diehl and Grieb; Dec. 11, 1906.

The feeding mechanism comprises the feed-dog 62 carried by the feed-bar 63 mounted at its rearward end on the pintles 64 of the feed-rocker 75 65 which is mounted on frame pintles 66, Fig. 1,

and has rigid with it a forked-arm 67, Fig. 5, embracing the feed-cam 68 on the main-shaft 46. The feed-cam 68 is of conventional form and is designed to impart a full feed-stroke to the feed-bar in 90° of rotation of the main-shaft. The 5 feed-bar 63 has a downwardly inclined forward extension 69 which carries a laterally projecting pin 70 entering a horizontal slot 71 in an intermediate feed-lift lever 72 which is fulcrumed on the bed frame at 73 and carries a lateral roller 10 stud 74 which enters the feed-lift cam-groove 15 75 in the hub of the hook-oscillating lever 57.

Mounted under the bed of the machine is a block 76 of insulating material carrying three fixed or stationary electrical contacts 77 and 15 three movable contacts 78 which are carried by the respective spring arms 79 mounted on the insulating base 76 and each carrying a follower-button 80 which is engaged by a respective track 81 of a cam-cylinder 82 of insulating material. 20 Engagement of any of the elevated portions of the tracks 81 of the cam-cylinder 82 with its respective track-follower button 80, closes the respective switch-contacts 77, 78 and energizes the particular coil of the solenoid *s* connected 25 in circuit therewith. The circuit is shown diagrammatically in Fig. 10, wherein it will be observed that each of the three solenoid coils is connected in series with a respective one of the three switches to a source of direct current. The 30 three tracks of the cam-cylinder 82 operate the switches in properly timed relation to coordinate the movements of the needle to the movements of the loop-taker.

The function of the thread-guide tube 45 is 35 to prevent slack needle-thread, given up by the take-up early in the downstroke of the needle-bar, from hitching or looping around the point of the needle 6 before such point enters the work. This guide-tube 45 is inclined toward and 40 terminates at its lower end below the usual needle-clamp 83 which grips the shank of the needle 6.

Operation

Starting at 0° position of the main-shaft 46 and cam-cylinder 82, Fig. 9, with the needle up, as in Fig. 1, and the switch in circuit with coil 13 closed, the oscillatory hook 52 of the loop-taker 51 is executing its return stroke and the feed-dog 50 has executed a little less than half of its work-feeding stroke. This will be apparent from Fig. 9, wherein the dotted line FB shows when the work-feeding stroke of the feed-dog begins and the line FE shows when the feed-stroke ends. The entire 55 feed-stroke is executed in 90° of motion of the main-shaft.

After the feed-stroke has ended, the needle begins its step-by-step descent at about the 80° position of the cam-cylinder 82 and finishes its 60 descent at about the 125° position, just after the loop-taker hook 52 has been retracted to loop-seizing position. As the needle-bar recoils slightly from the lower resilient cushioning washer 26, a loop of needle-thread is caused to bow outwardly 65 from the needle and this loop is immediately seized by the hook 52 and expanded as the hook 52 advances to cast-off position, Fig. 4, which is the extreme position to which the hook 52 advances after it has seized the needle-loop. The 70 slack thread given up by the take-up 28 on the downstroke of the needle 6 is available at this time and is drawn into the needle-loop as the latter is drawn out or expanded by the hook 52.

When the hook 52 is dwelling in cast-off posi- 75

tion, Fig. 4, preparatory to the execution of its reverse or return motion to loop-seizing position, the bobbin-case 53, which rests upon the hook-ring, is relieved of the drag produced by movement of the hook-ring and hence is not pressing forceably against the side of the usual rotation-restraining position-bracket 53' provided for the bobbin-case, as disclosed in U. S. Patent No. 1,388,114; G. Jackson; Aug. 16, 1921. At this time the needle is caused to execute, preferably, $\frac{3}{4}$ of its entire upstroke in one step, by the simultaneous energization of coils 13 and 14 and de-energization of the lowermost coil 15. This initial long step of the upstroke of the needle-bar elevates the take-up 28 and draws the cast needle-thread loop clear of the bobbin-thread case 53 but not up to the work. At about the 310° position, the needle-bar is caused to execute the final short step of its upstroke, by de-energization of coil 14, and the take-up completes the drawing up of the needle-loop at a comparatively slow speed and sets the stitch.

The initial long step followed by the final short step of the upstroke of the needle-bar and take-up avoids the snarling and kinking of the needle-loop which results when an attempt is made to draw the needle-loop all the way up to the work, at an accelerating speed, as in the machines of the prior art having solenoid-operated needle-bars and take-ups. Also, excessive hammering or overthrow blows against the cushioning washers are avoided and massive solenoid armatures are not required.

Furthermore I am, by the multiple-step-stroke solenoid-operation of the needle-bar and take-up or other reciprocatory part of a sewing machine, enabled to spread the times required for the execution of the strokes of the needle-bar, take-up, or other part, over appreciable time-portions of a complete stitch-forming cycle of operations of the machine as a whole, affording periods of slow motion intermediate extreme positions of the needle-bar, take-up, or other part, to better harmonize the operation thereof with the operation of other mechanisms of the machine.

Having thus set forth the nature of the invention what I claim herein is:

1. A sewing machine having a reciprocatory needle element, a complemental loop-taker element, and a work-feeder element, a multiple-step-stroke operating solenoid for one of said elements, and means to actuate the remainder of said elements in timed relation to said solenoid-operated element.

2. An electromagnet sewing machine having, in combination, an endwise reciprocatory needle device a complemental loop-taker device and a work-feeder device, a main-shaft, a solenoid having three or more energizing coils controlled by timing switches operated by the main-shaft to impart step-by-step movements to one of said

devices in each of two opposite directions, and means to actuate the remainder of said devices in timed relation to said one of said devices.

3. An electromagnetic sewing machine having, in combination, an endwise reciprocatory needle device a complemental loop-take device and a work-feeder device, a main-shaft, a solenoid having three or more energizing coils controlled by timing switches operated by the main-shaft to impart step-by-step movements to said needle-device in both its downstrokes and upstrokes, and means to actuate said loop-taker and work feeded devices in timed relation to said needle device.

4. An electromagnetic sewing machine having a solenoid-operated needle-bar, a needle-clamp carried thereby, a needle having a shank gripped by said needle-clamp and a reduced blade, a needle-bar-operated take-up, a loop-taker complemental to said needle, a bobbin, and a needle-thread guide-tube carried by said needle-bar and inclined toward the blade of said needle, said guide-tube terminating at its lower end below the needle-clamp.

5. An electromagnetic sewing machine having a frame formed with a bed and an overhanging bracket-arm terminating at its free end in a head, a needle-bar journaled to slide vertically in said head, a multiple-coil solenoid surrounding said needle-bar and disposed in its entirety in the upper portion of said head, and a spring-pressed presser-bar disposed in said head entirely below said solenoid.

6. An electromagnetic sewing machine having a frame formed with a bed and an overhanging bracket-arm terminating at its free end in a head, a needle-bar journaled to slide vertically in said head, a multiple-coil solenoid surrounding said needle-bar and disposed in its entirety in the upper portion of said head, a spring-pressed presser-bar disposed in said head entirely below said solenoid, and means in said head to adjust the pressure of the presser-bar spring.

7. A sewing machine having, a needle, a needle-bar, a needle-bar-operated thread take-up, a multiple-step-stroke solenoid for operating said needle-bar, a loop-taker complemental to said needle in the formation of stitches, and means to control the operation of said solenoid to cause the needle-bar to pause between the limits of its upstroke.

8. A sewing machine having a needle, a needle-bar, a multiple-step-stroke needle-bar-operating solenoid surrounding said needle-bar, a loop-taker complemental to said needle in the formation of stitches, means to control the operation of said solenoid to cause the needle-bar to pause between the steps of its upstroke, and a needle-thread take-up actuated by said needle-bar and disposed below said solenoid.

FREDERICK DIEHL.
